EXPANSIBLE LINK CHAIN FOR A BRACELET OR SIMILAR ARTICLE

Richard W. Mueller, Attleboro, Mass.

Application March 4, 1957, Serial No. 45,072

Term of patent 14 years

(Cl. D45—4)

Fig. 1 is a top plan view of an expandible link chain, embodying my new design with the links in contracted position;

Fig. 2 is a top plan view similar to Fig. 1 with the links in an expanded position, portions of the bottom links being visible;

Fig. 3 is a bottom view of the same link chain with the links in contracted position; and

Fig. 4 is a bottom view of the same link chain with the links in expanded position.

I claim:
The ornamental design for an expandible link chain for a bracelet or similar article, as shown.
